UNITED STATES PATENT OFFICE.

WARD W. WILLITS, OF CHICAGO, ILLINOIS, ASSIGNOR TO THE ADAMS & WESTLAKE COMPANY, OF ILLINOIS.

DESIGN FOR A LAMP-HANGER.

SPECIFICATION forming part of Design No. 19,832, dated May 6, 1890.

Application filed March 31, 1890. Serial No. 346,110. Term of patent 14 years.

To all whom it may concern:

Be it known that I, WARD W. WILLITS, of Chicago, in the county of Cook and State of Illinois, have invented and produced a new and original Design for Lamp-Hangers, of which the following is a specification, reference being had to the accompanying drawing, forming part of said specification.

My invention relates to that class of hangers in which the lamp is held rigidly suspended from the ceiling or roof, such as are usually employed in boats, railway-cars, and other vehicles.

In the accompanying drawing, the figure 15 shows a perspective view of the hanger, the lamp being in place therein.

A is a post resembling an inverted column having an annular base. From opposite sides of the lower part of the column A spring arms

C C, which curve downward and at their ²⁰ lower ends bend inward to meet the lamp-fount D. A shade or reflector E is affixed to the lower end of column A, occupying the space between the arms C C.

The leading feature of my design is the single column, which projects downward from the ceiling, provided with the arms C C, springing from the lower end of said column, descending and meeting at right angles to the lamp-fount below.

I claim as my invention—

The design for a lamp-hanger, substantially as shown and described.

WARD W. WILLITS.
